DESIGN FOR AN EXPANSIBLE LINK CHAIN FOR A BRACELET OR SIMILAR ARTICLE

Emil E. Fachon, Edgewood, R. I., assignor to
Bulova Watch Company, Inc., New York, N. Y.,
a corporation of New York

Application August 14, 1947, Serial No. 140,856

Term of patent 7 years

(Cl. D45—4)

To all whom it may concern:

Be it known that Emil E. Fachon, a citizen of the United States of America, residing at 12-A Sefton Drive, Edgewood, in the county of Providence and State of Rhode Island, has invented a new, original, and ornamental Design for an Expansible Link Chain for a Bracelet or Similar Article, of which the following is a specification, reference being had to the accompanying drawing, forming part thereof.

Fig. 1 is a plan view of a section of an expansible link chain for a bracelet or similar article, showing my new design;

Fig. 2 is an end view of the chain shown in Fig. 1 taken in the direction of arrows 2—2;

Fig. 3 is a side view of the chain shown in Fig. 1;

Fig. 4 is a perspective view of one of the top links of the chain;

Fig. 5 is a bottom view of the chain shown in Fig. 1;

Fig. 6 is a view similar to Fig. 1 but showing the links expanded.

I claim:

The ornamental design for an expansible link chain for a bracelet or similar article as shown.

EMIL E. FACHON.
